UNITED STATES PATENT OFFICE.

INA MOOBERRY TUNKS, OF LINCOLN, NEBRASKA.

DESIGN FOR A DOLL LAUNDRY BAG.

Application filed October 29, 1928. Serial No. 28,687. Term of patent 3½ years.

To all whom it may concern:

Be it known that I, INA MOOBERRY TUNKS, a citizen of the United States, residing at Lincoln, in the county of Lancaster and State of Nebraska, have invented a new, original, and ornamental Design for Doll Laundry Bags, of which the following is a specification, reference being had to the drawings, forming part thereof.

In the drawings,

I claim:

The ornamental design for a doll laundry bag, as shown.

INA MOOBERRY TUNKS.
